Specification of Letters Patent.

Patented Dec. 2, 1913.

Application filed December 22, 1910. Serial No. 598,736.

To all whom it may concern:

Be it known that I, FRIEDRICH STAMMSCHULTE, mining engineer, a subject of the German Emperor, and resident of Torgau, Germany, with the post-office address Bahnhofstrasse 13, have invented new and useful Improvements in Recuperators, of which the following is a specification.

The present invention relates to a furnace construction, which has one recuperator only in place of the gas- and air-regenerators, this recuperator, however, being reversible, contrary to other known recuperative systems, and thereby combining the advantages of the regenerative and the recuperative systems. The furnace may be constructed as a smelting or heating furnace, and with either one or two hearths. The invention contemplates the use of water gas as a preferable heating agent rather than common producer gas for the reason that the former has higher caloric properties than the latter and does not require preliminary heating. As the recuperator is continuously heated by the exhaust gases, the air will be heated progressively to higher temperatures and is reversed only, when this becomes necessary in consequence of the high temperature of the furnace. The periods of reversing may be limited to a minimum, reversing being necessary only, when the heads of the upper part of the furnace are being severely attacked by the exhaust gases. The periods at which the furnace will have to be reversed, depend on the operation of the furnace and can obviously not be determined in advance; generally it may, however, be taken as granted, that at most one-third as many reversals will be necessary with the present system, as with the regenerative system. The frequent reversal, which is unavoidable in finishing a charge in the regenerative furnace for the purpose of obtaining a heat as great and as uniform as possible, is entirely obviated with the present system.

The operation of the recuperator differs from that of other recuperator systems, in that it does not possess separate flues for the air and the combustion gases, but that the same flues conduct alternately air or combustion gases according to the respective position of the controlling valves, and the furnace will thus afford together with a

considerably simplified construction also 55 the advantages of the regenerative system.

The advantages of the recuperator compared with those of the regenerator consist in the smaller space required, a lower cost of construction, easier attendance and 60 cleaning and less repairing expense.

In the accompanying drawings Figure 1 shows one form of the furnace; Fig. 2 is a twin-furnace on a larger scale and Figs. 3 to 8 illustrate various modes of running this 65 twin-furnace. Fig. 9 is a vertical section of the recuperator taken on line 9—9 of Fig. 3; Fig. 10 is a vertical section of the recuperator taken on line 10—10 of Fig. 3; Fig. 11 is a horizontal section of the recuperator 70 taken on line 11—11 of Fig. 10; Fig. 12 is a vertical transverse section taken on line 12—12 of Fig. 9; and Fig. 13 is a vertical transverse section taken on line 13—13 of Fig. 9. 75

In Fig. 1 A is the smelting chamber, B the recuperator, C a change valve and D the chimney. E are openings through which either the heated air enters, or the combustion gases escape. The plain arrows → 80 indicate the current of the air being heated on its way to the smelting chamber, the feathered arrows → the path of the combustion gases from the smelting chamber to the chimney. By reversing the furnace the 85 air-passages are converted into passages for the combustion gases, which by reversing the valve C will not escape into the open air but into the chimney D. Referring more particularly to Figs. 1, 3, 5 and 7, and following the direction indicated by the arrows, it will be seen that the incoming air indicated by the plain arrows enters the recuperator through the lower horizontal duct 1 and is then distributed to a series of vertical 95 end ducts 2. A series of horizontal flues 3 communicate with the said vertical ducts 2 and conducts the air through the recuperator to a chamber 4 at the opposite end thereof. From the chamber 4, the air passes 100 through the outlet 5 to the furnace. It leaves the furnace in the form of waste gases and enters the recuperator through an opening 6 which communicates with the end chamber 7. Communicating with the end 105 chamber 7 are a series of horizontal flues 8. The horizontal flues 8 communicating with the chamber 7 correspond to the horizontal

flues 3 communicating with the chamber 2 and the various sets of the former are alternated with the various sets of the latter and juxtaposed as shown in Fig. 13, so that the waste gases in their passage through the recuperator heat the incoming air on the recuperative principle. A plurality of vertical ducts 9 communicate with the horizontal flues 8 and conduct the waste gases to the lower horizontal duct 10 by which they are discharged from the recuperator into the chimney D. By reversing the operation the incoming air is caused to enter where the waste gases had previously been discharged and the incoming air in reversing its direction through the recuperator will be caused to travel first through the flues which had previously conducted the waste gases. The path of the air and waste gases after reversal is indicated in Figs. 4 to 8, from which it will be seen that the air indicated by the plain arrows as before, enters through the opening 10, then up through the vertical ducts 9 and through the horizontal flues 8, which previously conducted the waste gases. From the horizontal flues 8, the air is conducted through the end chamber 7, opening 6, and through the furnace where it is converted into waste gases. The waste gases then being returned to the recuperator, enter the recuperator through opening 5 and are distributed to the horizontal flues 3 by means of the end chamber 4. It is to be noted that the horizontal flues 3, before the reversal, conducted the incoming air. After leaving the horizontal flues 3, the waste gases are collected by the vertical ducts 2 and are discharged through the lower duct 1 to the chimney D. The reversal, therefore, converts the recuperator into a regenerator since the incoming air is made to travel through the flues which had previously conducted the waste gases and the heat remaining in the walls of the flues serves to heat the incoming air.

In Fig. 2 *a* are the entrance nozzles for the water gas, *b* are the entrance nozzles for the hot air, which serve alternately as outlets for the exhaust gases. *c, c* are the two smelting hearths, *d* are the working doors and *e* the tapping points.

Figs. 3 to 8 show, how this twin-furnace is connected with a recuperator and the different modes in which they may be run. Here four change valves are provided. The plain and feathered arrows again indicate the path of the air and the combustion gases respectively. In Fig. 3 the two furnaces are heated by the flames on the right. Fig. 4 shows the reversal of this mode of operation, the central burners remaining idle or being employed additionally only and the flame spreading in one direction over the two furnaces. Fig. 5 shows one hearth, the right hand one, only being heated, the gases escap-

ing through the center; Fig. 6 is the same reversed. Figs. 7 and 8 show the same for the left hand hearth. By such means it is possible, to either keep both hearths running and to heat the one, when the other is finishing or to run one hearth only, while the other is being freshly charged.

The chief advantage of the twin-furnace lies in the possibility of finishing two charges of the same weight with the same amount of labor and about the same consumption of fuel, as would be required for a single charge in an ordinary furnace. In many instances also the otherwise indispensable spare Martin furnace will be superfluous, whereby the investment is reduced.

Now what I claim and desire to secure by Letters Patent is the following:

1. The combination of a smelting or heating furnace, a recuperator, passages connecting said furnace with said recuperator, said passages adapted to conduct either the waste gases or the air, and means to reverse the direction of flow of the waste gases and air in said passages.

2. The combination of a smelting or heating furnace, a recuperator having passages through which either the waste gases or the air may flow, a chimney connected with the recuperator, passages or conduits connecting the furnace with the recuperator, and means to reverse the direction of flow of the waste gases and the air in their travel through said passages.

3. The combination of a twin furnace, a recuperator connected therewith by gas conduits and constructed to act as a regenerator, as described, said furnace having at its ends and also at its intermediate portion openings for the entrance of air and for the escape of combustion gases, and means for interchangeably connecting said openings with said gas conduits to permit of running both hearths of the furnace alternately or only one of the same, as described.

4. The combination with a smelting or heating furnace, of a recuperator having one set of passages through which the air flows to the furnace and a second set of passages through which the waste gases from the furnace flow, said passages being so related that said gases heat the said air, passages connecting the recuperator with the furnace and means to reverse the direction of flow of the air and waste gases through said recuperator whereby the air is caused to travel through the passages through which the waste gases had previously traveled, said recuperator being thereby converted into a regenerator.

5. The combination with a furnace, of a recuperator provided with passages or flues therein, passages connecting the furnace with said recuperator, an inlet and an outlet associated with said recuperator, the air

admitted through the inlet being conducted through the recuperator, then through the furnace where it is converted into waste gases, said waste gases being conducted back 5 through the recuperator and discharged through said outlet, the passages in the recuperator being so arranged that the waste gases heat the incoming air, means to reverse the direction of flow of the air and 10 the waste gases so that the incoming air is admitted through the said outlet, then conducted through the recuperator by the passages which previously conducted the waste gases, then back through the furnace where

it is converted into waste gases and thence 15 through the recuperator again to the said inlet where they are discharged, the recuperator being thereby converted into a re-generator.

In testimony, that I claim the foregoing 20 as my invention I have signed my name in presence of two witnesses, this 8th day of December 1910.

FRIEDRICH STAMMSCHULTE.
